[57] CLAIM

The ornamental design for a combination printer and image scanner, as shown and described.

DESCRIPTION

FIG. 1 is a top, front and right side perspective view of a combination printer and image scanner showing our new design, with the cover in an open position;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and

FIG. 7 is a bottom plan view thereof.

FIG. 1

FIG. 2

FIG. 3

FIG. 4

FIG. 5

FIG. 7

FIG. 6
